CREEL

Frederick H. Bishop, Quincy, Mass., assignor to
Universal Winding Company, Boston, Mass., a
corporation of Massachusetts

Application July 27, 1931, Serial No. 553,294

16 Claims. (Cl. 242—131)

The present invention relates to creeling devices, and more particularly to creels having special adaptation for the delivery of yarn in package form to a warp beam or the like.

According to the common and generally prevailing practice, the warps are previously wound upon headed spools and withdrawn therefrom for delivery to a warp beam. Due to the presence of the heads, delivery of the warp yarn from the spool is invariably in a direction normal to the axis of rotation and tangential to the peripheral surface of the yarn package. The wound spools, which may average 400 to 600 in number, are individually loosely supported on trunnions and are rotated by the tension of the yarn in process of winding upon the warp beam. Due to the considerable number of warp yarns simultaneously wound, and the fact that tension upon individual warp ends varies in accordance with the diameter of the yarn package on the spool, the rate of winding according to this method is inevitably retarded, and ordinarily the yarn cannot be successfully removed at a rate greater than 65 to 70 yards per minute.

Aside from the inherent limitation upon the rate of winding, the yarn capacity of the spools is limited, which increases the frequency of doffing and as a result limits the production of the operator.

Certain suggestions have been made which contemplate the winding of the yarn on headless packages in conical or cylindrical form, and the withdrawal of the yarn from these packages in a direction generally aligned with the axis of rotation of the yarn package. The purpose and object of these constructions is to permit continuous warping through automatic replenishment of the yarn package upon exhaustion. They do provide, in addition, for a higher speed of winding operation than is possible of attainment with the familiar type of spool. On the other hand, these constructions are not adapted for the winding of single warp beams where the size and character of the yarn is frequently changed, nor do they avoid the common defect of all previous creeling apparatus due to the accumulation of lint upon the surface of the package, with the probability that this accumulation, either large or small, will be picked up by the warp strand in process of winding and incorporated in the finished product as a defect.

It is the purpose and object of the present invention to provide a relatively simple and highly efficient form of creeling device which may be readily set up, that is, supplied with its

complement of filled yarn packages, and which may be operated with any number of yarn packages at a high rate of speed, with a uniform tension, and with a freedom from accumulation of lint or foreign matter on the packages themselves. It is a further object of the invention to facilitate and simplify the doffing and replenishment of a complement of yarn packages on completion of a given beam winding operation.

With these and other objects in view, I propose to wind the yarn supply in the form of a conical or cylindrical package, preferably conical, upon a headless spindle or the like. I mount this wound yarn package in an inverted position upon a creeling device having a sufficient number of supports to accommodate the number of yarn packages in process of winding. Yarn guides are so arranged with respect to the package that the yarn is withdrawn from the package downwardly and in a generally axial direction, the package being in the meantime held stationary, and the yarn traversing thereabout in process of unwinding, as will be evident to those skilled in the art.

Due to the vertical and inverted position of the yarn package and the fact that the yarn strand extends downwardly and away from the surface of the conical package, the probability of lint accumulation or collection by the withdrawn warp strand, due to wiping of the peripheral surface by this strand, is substantially eliminated. In addition, I propose to reduce the possibility of accumulation upon the peripheral surface of the package by providing each package with a protective cover extending thereover in a manner to shield the package and collect any lint which may drop from above by gravity.

I provide for the convenient doffing of the packages upon completion of the winding operation through suitable mechanism designed to simultaneously release and discharge all or a portion of the packages upon manipulation of a suitable control. In addition to facilitating the doffing of the exhausted packages, the supporting spindles of the creel remain in a position convenient for the application of full yarn packages by the operator.

Still further features of the invention consist in certain novel features of construction, combinations and arrangements of parts herein-after described and claimed, the advantages of which will be obvious to those skilled in the art from the following description.

In the accompanying drawings illustrating the preferred form of the invention, Fig. 1 repre-

110

sents a front elevation of a creel with the upper screen removed; Fig. 2 is an end elevation of the creel shown in Fig. 1; Fig. 3 is a section upon the line 3—3 of Fig. 1, illustrating upon an enlarged scale the support for the packages and the position of the parts in process of doffing and replenishment; and Fig. 4 is a detail illustrating the relationship of the parts after doffing and replenishment, but before return of the 10 controlling mechanism to initial position for further doffing.

The creeling apparatus shown in the illustrated embodiment of the invention obviously may have provision for any desired number of 15 yarn packages. For simplicity, however, the illustrated embodiment is confined to six packages disposed in two rows of three packages each. Obviously, the number of rows or the 20 number of packages in each row can be varied as desired without modifying the theory of the invention.

As indicated, the creel may be provided with a supporting frame indicated generally at 10, and having oppositely disposed uprights 12 connected by generally transverse supports 14. The 25 yarn packages, which may be indicated at 16, are wound upon conical supports 18 to provide a generally conical package with the wound yarn traversing from end to end thereof in a manner 30 familiar to those skilled in the art. The creeling apparatus is provided with a series of depending supports in the nature of stationary spindles 20, each of which, as indicated in Fig. 3, is threadedly mounted in a head 22. The heads with the 35 supporting spindles are disposed upon a rock shaft 24, and maintained in proper spaced relationship by collars 26. Each head with its supporting spindle has provision for a limited movement with respect to the shaft through the 40 provision of the enlarged opening 28 for a purpose to be presently described. The head is normally caused to partake of the rocking movements of the shaft through the provision of a set screw 30 having a pointed end 32 which is received in and 45 engages with a similarly shaped recess 34 formed in the shaft. With the parts disposed in the position shown in Fig. 3, a limited rocking movement of the shaft serves to move the head and supporting spindle to the doffing position shown 50 in dotted lines. The conical winding support 18 is provided with a bore 40, which is received over the spindle 20 and with an annular recess 42 in the enlarged end, which is engaged by the out-turned end 44 by a spring latch 46 secured 55 to the side of the head 22 at 48. As indicated more particularly in Fig. 3, application of the cone 18 to the spindle in a lengthwise direction causes the insertion of the latch 46 within the 60 recess and the holding of the wound cone thereon in an inverted position.

Each rock shaft 24 is provided at one end with an arm 50, the two arms being interconnected by a link 52 to cause them to operate in unison. At the completion of the winding operation and 65 exhaustion of the yarn packages, the shafts are rocked through manual operation of a hand lever 54 to simultaneously project the supports 20 and cones 18 thereon from the vertical position shown in Fig. 3 to the inclined or doffing 70 position shown therein. This movement to doffing position is controlled by fixed stops 60 in the form of bars extending transversely across the machine, and designed to simultaneously engage with and release the spring latches 46, permitting the cones 18 to drop from the spindles

by gravity. The exhausted or partially exhausted cones are conveniently received and collected upon doffing by a receptacle 62 in the form of a screen surface 64 supported by curved arms 66 which are attached to the frame at 68 and are connected at their inner ends to shafts 70. As will be indicated, these receptacles are in a position to receive and collect the cones delivered from the inclined spindles, and for this purpose extend lengthwise of the machine beneath each row of packages, as indicated more particularly in Fig. 1. For the purpose of facilitating breaking of ends on the doffed packages, all of these packages are caused to lie upon the screen surfaces extending in the same direction. To this end the screens are provided with a series of deflector members 71, each in the form of an inverted V, as shown in Fig. 2, and disposed slightly at one side of the cone in a manner to engage the large end of the cone package and deflect the package into the position shown generally in Fig. 1, where the operator may readily engage and break the end and tie it into the corresponding end of the new package.

After the exhausted packages have been 100 doffed by movement into an inclined position and discharged by gravity, a new package may be conveniently applied to the spindle 20 in its forwardly extended inclined position. The application of this package when the head of the 105 cone is pushed upwardly thereon tends to move the supporting head 22 with relation to the rock shaft sufficiently to disengage the set screw from the receiving notch. This disengagement permits a slight movement of the spindle sufficient 110 to allow engagement of the latch with the recess in the head of the cone, when thereafter release of the package permits the entire assembly to return by gravity into approximately the vertical inverted position shown in Fig. 3. 115 This restoration to vertical inverted position takes place individually as each cone package is applied. Thereafter the rock shaft may be returned to its initial position, causing all of the set screws 30 to re-engage with the corresponding notches and restore the parts to the position shown in Fig. 3 in readiness for the next succeeding doffing operation.

It will be evident from the foregoing description that the yarn during its withdrawal from 125 the headless package extends generally axially or in the direction of length of the package in a downward direction, first passing beneath the rod 70 and thereafter being engaged by a tension 130 72 of conventional form. From the tension device the yarn is conducted to the warp beam or other tension device upon which it is to be wound.

It is important in all operations of this type that the surface of the yarn package shall be 135 maintained free of lint and accumulations of dust and dirt, as otherwise this lint is wiped off by the warp strand as it whips about the periphery of the package, collected thereon, and eventually carried into the finished material. 140 This accumulation of lint according to the present invention is eliminated through the provision of a protective shield 74, having the general form of an inverted cup extending completely over the top of the cone package and downwardly to enclose the upper portion. This cup-shaped shield is attached to a supporting disk 76 which, in turn, is clamped between the spindle 20 and the head 22, as indicated particularly in Fig. 3, this providing a convenient method of attach- 145

ment for the protective shield on each spindle mounting. As also indicated in Fig. 3, the shield is provided with an opening 78 through which the latch 46 projects, and sufficiently large to

- 5 permit necessary movements of the latch in locking and releasing the cone. Not only does the shield completely encompass the upper portion of the cone-shaped package, but in addition, due to the fact that the package tapers in-
10 wardly toward its lowermost portion, the possibility of collection of flying lint below the shield is substantially avoided. Although the shield serves the protective function of preventing accumulation upon the package, nevertheless it affords sufficient clearance about the upper portion of the package to avoid any engagement of the warp strand thereby due to its movement in unwinding from the package.

It will be self-evident that the exhausted yarn receptacles when doffed from the supporting spindles are discharged into the receiving tray immediately therebeneath, and extending in front of the machine. In this position the yarn strand extends from the exhausted package directly to the tension device, and is conveniently available for retying. In practice the operator may be provided with a carrier (not shown) which is provided with a supply of cones and pegs sufficient to fill one side of the creeling device. After the exhausted packages have been ejected from the creel holder, the operator removes a full cone from the carrier, places it in position on the support, and after latching allows it to drop down into the vertical position for tying in; breaking the end of the yarn adjacent the tip of the exhausted package, a knot is tied connecting the fresh package with the yarn strand in process of winding. The completely emptied or partially emptied package may then be placed upon the peg from which the full cone was removed. Obviously this mode of operation is contemplated only in those cases where more than one yarn receptacle is necessary to provide a supply for continuous winding. In many cases the yarn receptacle would contain a supply at least sufficient to provide for the cone winding operation, as each yarn package is capable on the average of supplying two warp beams, whereas the average creel spool contains only sufficient yarn supply for a single warp beam, approximately one-half as much.

It will be evident to those skilled in the art that the above-described construction provides a simple and exceedingly effective form of creeling mechanism from which the yarn may be unwound and delivered at high speed with a uniform tension on each yarn strand, with a minimum possibility of accumulation and collection of lint, and with a relative ease of doffing and replenishment of exhausted supply which makes the device particularly well suited for warp winding operations where the warp supply must frequently be changed between the winding of successive warp beams.

The term "exhausted package" is employed merely for descriptive purposes to define a package ready for doffing, and it is to be clearly understood that this term is not intended as necessarily descriptive of the condition of the package with relation to the yarn supply when actually doffed. In other words, the "exhausted package" so-called, frequently if not invariably, contains some small residuum of yarn supply, or in fact may be doffed because winding of the warp has been completed. "Exhausted pack-

age" therefore means merely a package the useful function of which has been exhausted and which is in condition for doffing.

What is claimed is:

1. A creel comprising a plurality of supports designed to individually retain a plurality of yarn packages in substantially vertical inverted position, means for delivering a yarn strand downwardly from the package, a protective shield associated with the support and projecting over the yarn package when mounted thereon, means associated with the support for detachably latching the yarn package thereto, and means for releasing the latch to permit the discharge of the package by gravity from beneath the protective shield. 80

85 2. A creel comprising a plurality of supports designed to individually retain a plurality of yarn packages in substantially vertical inverted position, means for delivering a yarn strand downwardly from the package, a protective shield associated with the support and projecting over the yarn package when mounted thereon, means extending through the shield for detachably latching the yarn package thereto, and means located above the shield for releasing the latch to permit the discharge of the package by gravity from therebeneath. 90

100 3. A creel comprising an inverted support, an inverted cup-shaped shield secured to the support, a latch mounted upon the support and extending downwardly through the shield, a yarn package received upon the support and engaged by the latch, means for rocking the support from a vertical inverted position to an inclined doffing position, and means for engaging the latch upon removal of an inclined doffing position to actuate the latch and release the yarn package by gravity from beneath the shield. 105

115 4. A creel comprising a plurality of downwardly extending yarn-supporting members adapted to receive an inverted package delivered thereto, means for latching the inverted package in place on the support, means for guiding yarn withdrawn therefrom, and manually controlled means for simultaneously releasing a series of latches to discharge yarn packages therefrom. 120

125 5. A creel comprising a plurality of permanently downwardly extending yarn-supporting members adapted to receive an inverted package delivered thereto, means for latching the inverted package in place on the support, means for guiding yarn withdrawn therefrom, and means for simultaneously moving yarn supports 130 from winding to doffing position and discharging yarn packages therefrom.

135 6. A creel comprising a series of permanently dependent yarn supports, means for mounting the supports to rock from a substantially vertical or winding position into an outwardly inclined doffing position, means for latching yarn packages upon the supports in inverted position, means for simultaneously releasing the latches upon movement of the supports from winding to 140 doffing position, and means permitting re-engagement of individual latches upon application of a fresh yarn package to the accompanying dependent support.

145 7. A creel comprising a series of inverted yarn supports, means for mounting the supports to rock from a winding position into an outwardly inclined doffing position, means for latching individual yarn packages upon the supports, an abutment for simultaneously releasing the 150

- latches upon movement of the supports from winding to doffing position, and manually controlled means permitting re-engagement of the latches.
5. A creel comprising a series of permanently dependent yarn supports, means for mounting the supports to rock from a winding position into an outwardly inclined doffing position, means for individually latching inverted yarn packages upon the supports, means for shielding the packages so mounted, and means for simultaneously releasing the latches upon movement of the supports from winding to doffing position. 80
6. A creel comprising a series of inverted yarn supports, an umbrella shield connected with each support, means extending through the shield for latching the yarn package to the support beneath the shield, means for guiding the yarn strand in a downward direction away from the package, and means for releasing the exhausted package to drop from the support by gravity. 85
7. A creel comprising a supporting rock shaft, a series of yarn supports depending in spaced relation from the rock shaft and normally maintained in a vertical inverted position, and means for normally moving the supports into an outwardly extending doffing position on movement of the rock shaft having capacity for manual disconnection from the rock shaft to permit restoration of individual supports to a normal vertical position. 90
8. A creel comprising a supporting rock shaft, a series of yarn supports depending in spaced relation from the rock shaft and normally maintained in a vertical inverted position by gravity, and connections between the rock shaft and supports for normally moving the supports into an outwardly inclined doffing position, having provision for lateral movement of the support with relation to the rock shaft to release the connection and allow return of the support to normal vertical position. 95
9. A creel comprising a supporting rock shaft, a series of heads loosely received on the rock shaft and having bearing openings larger than the rock shaft to permit lateral movement with relation thereto, means for normally connecting the head and rock shaft for rocking movement, a supporting spindle connected with each head, and a spring latch connected to the head and adapted to engage and hold a yarn package. 100
10. A creel comprising a series of dependent inverted yarn supports normally maintained in a vertical winding position and adapted to receive headless yarn packages thereon, means for withdrawing yarn from the packages in a direction substantially lengthwise of the package, means for detachably latching the packages to the supports against the force of gravity, means for simultaneously moving the supports and yarn packages thereon into an inclined doffing position and automatically releasing the packages to permit discharge in such a position, and means for individually releasing each latch upon application of a new package to the accompanying support. 105
11. A creel comprising a series of supports for receiving and holding yarn packages in inverted position, and a protective shield associated with each support and extending over the upper portion of each yarn package to prevent the accumulation of lint thereon, and a latch extending from above the shield and engaging with the yarn package from below. 110
12. A creel comprising a support for an inverted yarn package, a protective shield above the support, a guide for leading the yarn strand downwardly and generally lengthwise of the package upon delivery therefrom, means for moving the support and protective shield into an inclined inverted doffing position, and a latch for the yarn package supported from above the shield and released upon movement of the support into an inclined doffing position. 115
13. A creel comprising a series of supports for receiving and holding yarn packages in inverted position, means for moving the supports into an inclined doffing position, means for receiving the packages discharged therefrom, and means for engaging and deflecting the packages in a common direction during the doffing operation. 120
- FREDERICK H. BISHOP. 125
14. A creel comprising a series of supports for receiving and holding yarn packages in inverted position, and a protective shield above the support, a guide for leading the yarn strand downwardly and generally lengthwise of the package upon delivery therefrom, means for moving the support and protective shield into an inclined inverted doffing position, and a latch for the yarn package supported from above the shield and released upon movement of the support into an inclined doffing position. 130
15. A creel comprising a series of supports for receiving and holding yarn packages in inverted position, and a protective shield above the support, a guide for leading the yarn strand downwardly and generally lengthwise of the package upon delivery therefrom, means for moving the support and protective shield into an inclined inverted doffing position, and a latch for the yarn package supported from above the shield and released upon movement of the support into an inclined doffing position. 135
16. A creel comprising a series of supports for receiving and holding yarn packages in inverted position, and a protective shield above the support, a guide for leading the yarn strand downwardly and generally lengthwise of the package upon delivery therefrom, means for moving the support and protective shield into an inclined inverted doffing position, and a latch for the yarn package supported from above the shield and released upon movement of the support into an inclined doffing position. 140
17. A creel comprising a series of supports for receiving and holding yarn packages in inverted position, and a protective shield above the support, a guide for leading the yarn strand downwardly and generally lengthwise of the package upon delivery therefrom, means for moving the support and protective shield into an inclined inverted doffing position, and a latch for the yarn package supported from above the shield and released upon movement of the support into an inclined doffing position. 145
18. A creel comprising a series of supports for receiving and holding yarn packages in inverted position, and a protective shield above the support, a guide for leading the yarn strand downwardly and generally lengthwise of the package upon delivery therefrom, means for moving the support and protective shield into an inclined inverted doffing position, and a latch for the yarn package supported from above the shield and released upon movement of the support into an inclined doffing position. 150
